DESIGN FOR A GAME BOARD OR THE LIKE

Domenic A. Valvano, Linden, N. J.

Application September 1, 1936, Serial No. 64,674

Term of patent 3½ years

To all whom it may concern:

Be it known that I, Domenic A. Valvano, a citizen of the United States and a resident of Linden, in the county of Union and State of New Jersey, have invented the new, original, and ornamental Design for a Game Board or the Like, of which the following is a specification, reference being had to the accompanying drawing forming part thereof, in which

The figure shows a plan view of a game board embodying my new design.

The game board is of no appreciable thickness and its face is disposed in a single horizontal plane, all of the game features being flush with the surface.

I claim:

The ornamental design for a game board or the like substantially as shown and described.

DOMENIC A. VALVANO.
